UNITED STATES PATENT OFFICE.

JOHN E. GREENAWALT, OF DENVER, COLORADO.

CHARGE-CAR.

1,104,491.

Specification of Letters Patent. Patented July 21, 1914.

Application filed October 16, 1912. Serial No. 726,188.

To all whom it may concern:

Be it known that I, JOHN E. GREENAWALT, citizen of the United States, residing at Denver, in the county of Denver and State of Colorado, have invented certain new and useful Improvements in Charge-Cars, of which the following is a full, clear, and exact description, reference being had to the accompanying drawings, forming a part hereof.

My invention has relation to improvements in charge-cars; and it consists in the novel features of construction more fully set forth in the specification and pointed out in the claims.

In the drawings, Figure 1 is a vertical longitudinal section of a series of two sintering pans taken on the line 1—1 of Fig. 2, showing the application of my charge-car thereto, the car being shown in cross-section, parts in said figure being in elevation; Fig. 2 is a vertical cross-section on the line 2—2 of Fig. 1; Fig. 3 is a vertical transverse section of the charge-car taken on the line 3—3 of Fig. 4, a sectional view of one end of the sintering pan being likewise shown to illustrate the relative position of the two when the car is in service; Fig. 4 is a rear elevation of the charge-car with the gates or doors swung to closed and locked position, a part of the car being broken away; Fig. 5 is a horizontal section on the zig-zag line 5—5 of Fig. 3 of the charge-car only; and Fig. 6 is a sectional view on the order of Fig. 3, showing however, the doors or gates swung open, and the material discharging into the sintering pan.

The present invention is directed to the charging of pans or pots or equivalent containers for treating or sintering ores by what is known as the intermittent system; that is to say, a system where a predetermined charge is sintered in a given pan, a series of pans being usually employed to permit the charging of one pan while the material in the others is undergoing treatment. In such a system the method of treatment is to sinter the charge by a downward burning process, the pans or pots being provided with a perforated bottom to support the charge, the air or supporter of combustion being drafted through the charge and is perforated (or equivalent) support. In such a process it is imperative not only that the material composing the charge shall be distributed uniformly in the

pan, but that when once distributed it shall be homogeneous throughout. In other words care must be exercised that the charge shall be of substantially uniform thickness, 60 and uniform density, such a condition being indispensable to the uniform and even penetration or progression of the zone of combustion from the top to the bottom of the charge. It is evident that if the charge be 65 packed or dense at one point and loose at another, the resistance to the passage of the air (which supports the combustion of the fuel contents of the charge) will not be uniform, the loose portions offering the least 70 resistance to such passage and being sintered first, the denser portions retarding such passage and hence destroying the uniform progression of the zone of combustion. In the loose portions the fuel contents will be the 75 first to be consumed, and hence these portions will be sintered first. The porosity of these sintered portions will thus permit the drafted air to percolate or flow with little obstruction toward the exhauster, the air 80 taking the paths of least resistance, thus leaving the denser portions of the charge and those less permeable to the air, practically unsintered. In other words the 85 "leaks" through the loose sintered spots destroy the suction intended for the denser spots and thereby interfere with the successful roasting or sintering action of the unsintered portions of the charge. In the ordinary charge-car the entire charge is 90 dumped at one place, and in dumping, the weight and momentum of the upper portions of the charge pack and compress the lower portions at the place of dumping, so 95 that even after the charge has been leveled off it is found that it is much denser at the places where the charge was dumped than elsewhere. In the system referred to the pans have an area of from eighty to ninety square feet, so it is evident that to level off 100 a charge of such extended area by hand becomes a very difficult and tedious matter; and unless the charge is accurately and uniformly leveled, the resistance to the flow of air through the charge will vary considerably, being greatest where the charge is 105 densest.

It is apparent from the foregoing that the ideal conditions for obtaining the best results are to deposit the charge into the 110 pot or receptacle in such a way as to maintain not only a uniform thickness in the

charge throughout, but at the same time to preserve absolute homogeneity in the material so as to preserve a uniform density and porosity throughout the mass. Under 5 such conditions when the entire surface of the charge is simultaneously ignited, the zone of combustion will progress through the mass uniformly and thereby result in a uniform, homogenous, sintered product. It 10 is the object of my invention to bring about these ideal conditions in the matter of depositing the charge in the treatment receptacle, the description of the details of the invention being as follows:—

15 Referring to the drawings, 1 represents a pan or treatment receptacle which in practice may be of any convenient size, the dimensions of that here shown being about twelve feet in length, seven feet wide, and 20 two feet deep. The pan is provided with grates G collectively forming a perforated bottom or support for the charge of material *m* deposited thereon as well understood in the art. The pan or receptacle is 25 provided with hollow trunnions 2 disposed below the grates and the charge supported thereon, and in free communication with the chamber 3 between the grates and the bottom of the pan. The trunnions of each pan 30 (there being any number of pans to a plant) communicate with a box or casing 4 from which lead pipes 5, 5, to a suitable fan or exhaust F, the latter being driven by an electric or equivalent motor M. When the 35 exhaust is in operation, the air and gases are drawn evenly through the charge and its supporting grates, into the chamber 3 and out through the hollow trunnions 2, boxes 4, pipes 5, into and out of the 40 exhaust. The pan is freely rotatable about the common axis of the trunnions (being the longitudinal axis of the pan) and when the charge thereon has been sintered, the pan is rotated (by hand or otherwise) about 45 said axis sufficiently to dump the charge onto a chute or grizzly 6 whence it is discharged into a car T.

Disposed adjacent the sides of the pan are rails R for the support of the wheels 7 at 50 the ends of the stationary axles 8 from which the igniting hood H is suspended. The hood may be moved along the rails R over any pan and lowered to engage with the walls thereof thereby forming above the 55 charge an ignition chamber C to which the necessary fuel (gas or liquid hydrocarbon spray) is admitted for igniting the surface of the charge. The charge once ignited, the hood may be moved to the next pan, the exhaust 60 maintaining the combustion of the charge previously ignited by drawing the air downward through the charge and its support.

The foregoing represents the general 65 character of treatment vessel in conjunction

with which my present invention is employed, and is here described in a general way only, constituting as it does, subject-matter for an independent patent. It is to be observed however, that I do not limit the application of my charge-car to the particular treatment receptacle here alluded to, my invention being capable of use with any receptacle intended to be filled with a charge. However, taking the present pan as an example, I will now describe the charge-car and the manner of its co-operation with the particular pan or pans here selected by way of example:—Disposed above the series of pans 1 and in parallelism with the rails R, are pairs of rails 9, 9, forming a guide-way or track for the travel of the wheels 10 of the charge-car or holder 11 rigidly depending from the truck-frame 12 carrying the wheels. The track thus formed (by the rails 9, 9) prevents both vertical and lateral displacement of the charge-car and the latter runs true and is maintained in perfect alinement with the pan over which it is advanced. The car is moved back and forth on its rails by means of an endless cable c secured to the bar d of the truck-frame, and guided over sheaves or rollers r and winding and unwinding over a drum (not shown) operated by an electric motor (not shown), there being no novelty in this, such features being common in hoisting apparatus. The charge-car is preferably of the form as shown, that is to say with vertical side walls and downwardly converging front and rear walls, the side walls terminating in bottom extensions or wings w which project forward or in the direction the car is advanced while discharging. Mounted in bearings 13 at the base of the front wall of the car is a shaft 14 to which is secured the main or charge-supporting door or gate 15 operating freely between the side walls of the car. To the outer projecting terminals of the shaft 14 and swinging in planes beyond the side walls of the car, and projecting in a direction opposite from the gate 15 are weighted balance levers or members 16 by means of which the gate may be readily manipulated for purposes of regulating the rate and volume of discharge.

Mounted at the base of the rear wall in brackets or bearings 13' secured to the bottoms of the side walls is a shaft 17 which carries the locking gate 18, the latter supporting the gate 15 when the gates are closed. From the center of the shaft 17 and projecting in a direction opposite from the gate 18 is an arm or balancing lever 19 which is provided with a detachable pin or keeper 20 preferably secured to a chain 21 to prevent loss of same. The arm 19 is held in its depressed position (and the gate 18 closed) by a latch arm 22 pivoted at its up-

per end between a pair of ears or lugs e , e , on the plate 23 secured to the rear wall of the car, the free end of the latch-arm bearing against the pin 20 which thus acts as a keeper. By knocking out the pin, the latch is released, leaving the gates free to open. The locking gate 18 is so weighted that when released it will drop until arrested by the arm 19 striking the bumpers 24 (which may 10 be adjusted by screwing or unscrewing the same within their sockets 25 as shown, or by any other means suggesting themselves to the skilled mechanic), the opening of the gate which is in the path of discharge of the material being however assured by the pressure of the charge in the car. The edge of the gate 18 serves as a leveler for the charge deposited in the pan, the bumpers 24 being so adjusted as to arrest the arm 19 (and hence the gate) when the edge of the 20 gate is level with the top of the sintering pan across which the charge-car is moving (Fig. 6). The fixed sides or wings w of the car extend down to within one inch of the 25 top of the pan, this insuring sufficient clearance to enable the car to be moved back and forth over the remaining pans without danger of interference or fouling.

The operation may be described briefly as follows:—The material m composing the charge is comparatively fine and in order to prevent these fines from being drawn through the grates or equivalent perforated supporting bottom, a thin layer (from one 35 quarter to one inch in thickness) of coarse material m' reasonably free from combustible matter is first spread over the grates such a layer being susceptible of ready removal from the grates after the charge is sintered. The available depth of the pan or receptacle 1 is that between the top surface of the 40 grates and the upper edges of the pan, this being about twelve inches so that the material discharged from the car into the pan 45 has a comparatively short drop, it being remembered that the bottoms of the sides of the car are only about one inch above the edges of the pan. A car will hold one charge, that is to say, enough to make a bed. about a foot thick and of an area equal to 50 the area of the pan (eighty-four square feet). The manner of filling the car is immaterial as that may be done in any convenient way known to the art. To charge 55 an empty pan the car is moved up over the pan in such position that when the locking gate 18 is released the leveling edge thereof will come just over the inside edge of the end wall of the pan (Fig. 6). By seizing 60 the balance arm 16 the gate 15 may be opened to any required degree. It will be seen that this gate 15 (which we may term the charging gate) in opening, swings forward or toward the front of the car, allowing 65 the material to flow from the car rear-

wardly or in a direction opposite to that in which the car is moved across the pan in the charging operation. This rearward flow of the material insures the filling of the corners of the pan at the end at which the 70 charging of the pan begins, the material flowing into said corners as indicated by the arrow in Fig. 6. Once the charging of the pan is begun, the car is moved across the pan, the operator so controlling the gate 15 75 as to permit the discharge of the material from the car to be strictly commensurate with the rate of speed of the car over the pan. Since the more or less moist material practically rolls from the car and its maximum drop is restricted to about a foot in reaching the bottom of the pan (by "bottom" is here meant the grate surface on which the material is deposited), it follows that a substantially gentle deposit of the 80 material results as compared with a precipitation in cases where the material is bodily dumped into the pan. The gentleness of the deposit is further insured by the rearward discharge of the material from the car (that is, a discharge in a direction opposed to the direction of traverse of the car across the pan while discharging) the car receding as it were from the material while the latter is discharging. This 90 prevents packing of the fines and insures uniform porosity for the mass during the sintering operation. As the car moves across the pan, the leveling edge of the locking door 18 levels the charge, making an even surface, 95 the bumpers 24 being adjusted to bring this edge into the plane of the upper edges of the pan. It will be observed that the bottom of the car opens in such a way as to practically form a chamber closed on three sides, 100 namely the door 15 and the side wings w , w , the door directing the material rearwardly into the receptacle and depositing the same practically level. The balancing levers 16 are important as by means of them 105 the gate 15 is kept under perfect control. The adjustment of the leveling edge of the gate 18 is also important; if this edge were fixed it would be bumping against and scraping the tops of other pans and charges 110 and would interfere with the free operation of the car back and forth.

It will be seen that during the pan-filling operation, that is, during the discharging of the contents of the car, the latter is moved forward across or over the several pans of the series, a single charge filling a pan, the car being empty by the time it reaches the end of the pan opposite from that at which the filling operation began. As the car 120 moves across the pan the deposited material is accurately leveled off by the edge of the gate 18 as described, and the charge is in an ideal condition for treatment. The car is then returned or moved back to the source 125 130

of supply where the gates are closed, and the car is ready to receive the next charge. The filled car is then moved forward to the next pan of the series, the locking gate is released and this pan filled in the same manner. When the gates are closed the car is free to move across all the pans owing to the one inch clearance between the tops of the pans and the wings *w*, *w*, of the car. 15 This clearance is fixed, and is sufficient to permit the car to pass over the several pans without fouling or scraping, and is to be distinguished from the variable clearance between the tops of the pans and the edge 20 of the leveling gate 18 which can be regulated by a careful adjustment of the bumpers 24 by which the gate is arrested.

Owing to the low (12 inch) drop of the material from the car to the depositing surface formed by the grates *G*, the material does not break as a result of precipitation, but on the contrary flows as a continuous and integral stream out of the car, depositing uniformly over the grates with the progressive advance or traverse of the car 25 across the pan. It is this integrity in the flowing or rolling stream of material which contributes to preserve the homogeneity, there being an entire absence of packing owing to this reduced drop and to the further fact that the car moves in one direction while it is discharging in the opposite direction.

Features shown but not alluded to are 30 either well known or form subject-matter foreign to the present application, and hence not here described.

Having described my invention, what I claim is:—

40 1. In a traveling charge-car, a holder having inclosing walls and open at the bottom, a movable gate disposed across said open bottom for supporting the charge in the holder, a movable member on the holder adapted to release the gate from its charge-supporting position, and operating to be depressed below the bottom edge of the holder when moved to effect the release of the gate aforesaid, whereby the member may serve 45 as a leveler.

55 2. In a charge-car, a holder having inclosing walls and open at the bottom, a gate hinged on one side of the holder and operating to be swung across the open bottom for supporting the charge, a locking-gate hinged opposite the first gate and holding the latter in its charge-supporting position, the edge of the locking-gate being adapted to be depressed below the bottom edge of 60 the holder when swung in proper direction to release the first gate.

65 3. In combination with a receptacle having a depositing surface for the support of a charge, a charge-car movable across the receptacle, a gate for supporting the charge in

the car for a closed position of the gate, a movable member on the car coöperating with the gate and permitting a release thereof for purposes of discharging the contents of the car, said member serving as a leveler 70 for the material deposited in the receptacle upon its discharge from the car.

4. In a charge-car, a holder for the charge, a pair of doors coöperatively supporting the charge in the holder for a closed position of the doors, and releasing the charge with an opening of the doors, and means on one of the doors for leveling the discharged contents by a movement of the car in a given direction.

5. In a charge-car, a holder for the charge, a pair of doors coöperatively supporting the charge in the holder for a closed position of the doors and releasing the charge with an opening of the doors, means on one of the doors serving as a leveler for the discharged contents during the movement of the car thereover, and balancing members on the opposite door for actuating said door and regulating the flow of the discharging contents.

6. In a charge-car, a suitable holder for the charge, a pair of bottom doors or gates hinged to the holder and overlapping one another for a closed position of the doors, means for effecting a release of one of the doors from its closed position and thereby releasing the opposite door, and means on the door first released for leveling the discharged contents by a movement of the car 100 thereover in a given direction.

7. In a charge-car, a suitable holder for the charge, a pair of gates hinged at the bottom of the holder and interlocked for a closed position of the gates, means for effecting a release of one of the gates from its closed position and thereby releasing the opposite gate, and means on the first gate for leveling the discharged contents by a movement of the car thereover in a given direction.

8. In combination with a receptacle having a depositing surface for the support of a charge, a charge-car movable across the receptacle, gates on the bottom of the car for releasing the material into the receptacle and discharging the same over the depositing surface in a direction opposite to the travel of the car, and means on one of the gates for leveling the deposited material 115 during the movement of the car across the receptacle.

9. A charge-car comprising a suitable open-bottomed holder, a gate hinged to the wall of the holder and extending across the opening of the bottom, a locking gate hinged opposite the first gate and engaging the latter along the bottom for a closed position of the gates, means on the outside of the holder for holding the second gate in its locking 125 position.

position, and suitable controlling levers on the first gate.

10. A charge-car comprising a suitable open-bottomed holder having a pair of hinged gates in interlocked relation for a closed position of the gates, means for releasing the gates, and means on the holder for arresting the movement of one of the gates at a predetermined point of the opening swing of said gate.

11. A charge-car comprising a holder having opposing parallel walls and contiguous downwardly converging walls and provided with an open bottom, extensions leading from the parallel walls beyond the bases of the converging walls, a gate hinged at the base of one of the converging walls and adapted to close the bottom of the holder, balancing members leading from the hinge-axis of the gate, a second gate hinged at the base of the opposite converging wall and supporting the first gate for a closed position of the gates, a member leading from the hinge axis of the second gate, and formations on the wall of the holder for arresting said member and thus limiting the outward swing of the second gate.

12. A charge-car provided with side, front, and rear walls, and open at the bottom, and an oscillatable discharge-controlling member on the car projecting below the bottom of the car and serving as a leveler.

13. A charge-car comprising a holder open at the bottom and provided with front and rear walls, and side walls extending below

the said front and rear walls, a gate hinged at the base of the front wall operating between the extensions, and closing across the open bottom of the car, balancing levers coupled to the hinge axis of the gate at 40 points beyond the side walls, a locking gate hinged at the base of the rear wall and engaging the bottom of the first gate for a closed position of the gates, a balance arm for the locking gate oscillating opposite the 45 rear wall of the holder, a hinged latch coupled to the rear wall, a movable keeper on the balance arm engaging said latch for a closed position of the gates, and devices projecting from the rear wall of the holder and 50 serving as bumpers, for arresting the balance arm of the locking gate upon release of the latch from its keeper and thereby limiting the outward swing of said gate, for the purpose set forth.

14. A charge-car comprising a holder having an open bottom, a hinged gate for directing the discharge of the contents in one direction, means for preventing escape of the material over the ends of the gate during 60 such discharge, and means for moving the car in a direction opposite to the general direction of flow of the discharging material.

In testimony whereof I affix my signature, in presence of two witnesses.
